BRILLIANT TYPE DIAMOND AND METHOD
OF CUTTING THE SAME

Max Suderov, New York, N. Y., assignor to Patented Diamond, Inc., New York, N. Y., a corporation of New York

Continuation of application Serial No. 527,737, March 23, 1944. This application July 21, 1944, Serial No. 545,968

14 Claims. (Cl. 63—32)

This invention relates to a method of cutting and polishing diamonds; more particularly, to a method of cutting and polishing the brilliant type of diamonds, and the resultant product.

This application is a continuation of my application Serial No. 527,737, filed March 23, 1944.

The diamond most commercially available in the trade today is the brilliant type. Whether such diamonds are in sizes varying from twenty to the carat to one or two carats, they have found greatest favor commercially. Because of their symmetrical proportions, they lend themselves readily to brillanteering operations conducive, to a certain extent, to quantity production methods, as distinguished from odd shapes, which may be characterized as custom made, where the labor of brillanteering or faceting formation is of no material consequence.

In the production of the brilliant type of diamond, the experienced diamond cutter takes advantage of the crystallographic axes of the diamond crystal for securing the optimum polishing effects which, based upon the fact that the crystallographic axes are at right angles to each other, determine the division or blocking for the grinding operation to form the facets, other than the table and culet, by a series of symmetrical facets most nearly normal to the growth lines or grain, and that with this as a guide, to thereupon polish perpendicular to the grain. This has resulted in a group of facets based, first, upon the cross work of four cuts, and upon an octagon working, with intermediate brillanteering facets thereupon being formed which are small multiples of the octagon, in order to secure, exclusive of the table and culet, thirty two facets on the bezel or crown and twenty four facets on the pavilion or base.

Efforts have been made, as known to me, to provide pentagonal facets by dividing the arrangement of the facets in both the crown and pavilion on the basis of triangulation, thrice repeated, thereby using nine basic or blocking facets.

Thus, by the prior method based upon making four blocking cuts or cross work and the octagon work, only four main phases of the crystallographic formation of the diamond have been taken into account, whereas in the triangulation system, the crystallographic construction of the diamond has been disregarded in an effort to give particular contour to a number of facets in the pavilion and crown, respectively.

The former system, operating on the basis of the four main blocking cuts, places a limitation

upon the faceting operation; the triangulation system, being concerned with peculiar shapes of facets, requires unusual skill, in view of the unsymmetrical characteristics of the basic facets and their relation to the crystallographic structure of the diamond. The triangulation system, therefore, requires unusual skill and patience of the so-called worker who performs the blocking work and of the brillanteer. The judgment of these workers must be precise, with constant observation as to the effect of their work, if at all feasible. The triangulation system, therefore, does not lend itself readily to a commercial production of a brillanteered diamond.

I have discovered that symmetry of division of the blocking cuts, tending towards an augmenting of the beauty of the diamond and an increased number of facets, may be secured by departing both from the octagon blocking system and the triangulation blocking system, by a division of the basic blocking facets both for the crown and the pavilion, using either twelve or sixteen basic or blocking facets, which may thereafter be divided into multiples of twelve or sixteen, thus securing simpler, even though increased brillanteering facets. As a consequence, the brilliance of the diamonds may be increased and the brillanteering operation proceed with a higher degree of uniformity to the touch of the brillanteer. As a consequence, also, the beauty of the brilliant type of diamond is enhanced and the speed of production increased out of proportion to the increased number of facets.

Accordingly, it is an object of my invention to provide a method for brillanteering diamonds to provide a diamond of the brilliant type, in which both the crown and the pavilion or base have their facets formed on the basis of symmetrically arranged basic or blocking facets, which are symmetrical with the crystallographic axes in excess of eight, thus departing from the number of primary blocking cuts formed on the ordinary type heretofore commercially produced in forming the brilliant type of diamond, whereby simplicity of blocking and brillanteering is made available.

It is also contemplated by my invention to provide a cut or faceted diamond of enhanced beauty, as to contour and brilliance, heretofore not acquired.

To attain these objects and such further objects as may appear herein or be hereinafter pointed out, I make reference to the accompanying drawings, forming a part hereof, in which— Figure 1A discloses diagrammatically, in per-

spective, the octahedron crystal, showing generally the crystallographic axes and grain direction of the diamond crystal; also showing superimposed thereon the basic facets in relation to the crystallographic axes, in accordance with one embodiment of my invention;

Figure 1 is a top plan view of a diamond showing the basic facets, in accordance with one embodiment of my invention;

Figure 2 is a bottom view of the diamond shown in Figure 1, in which the basic or blocking facets for the crown are shown;

Figure 2A is a side elevation view of Figure 1;

Figure 3 is a top plan view of a diamond cut from Figure 1, with the brillianteering facets;

Figure 4 is a bottom view showing the completed brillianteering facets on the pavilion;

Figure 5 is a side elevational view of the diamond, showing the complete crown and pavilion facets;

Figure 6 is a plan view of a diamond cut in accordance with my invention, to embody a so-called Swiss cut;

Figure 7 is a bottom view of the diamond shown in Figure 6, to display the pavilion facets;

Figure 8 is a side elevational view of the diamond in accordance with my invention as shown in Figures 6 and 7;

Figure 9 is a side elevational view of a diamond cut in accordance with another embodiment of my invention;

Figure 10 is a side elevational view of a diamond in accordance with a still further embodiment of my invention;

Figure 11 is a top view of another embodiment of my invention, viewed from the direction of the table of the diamond;

Figure 12 is a view of the diamond in accordance with Figure 11, viewed from the pavilion of the diamond;

Figure 13 is a side elevational view of the diamond shown in Figures 11 and 12;

Figures 14, 15 and 16, are, respectively, the table, pavilion and side views of a diamond formed with the blocking cuts by conventional methods.

Making reference to the drawings, in Figure 1A I have diagrammatically shown the natural octahedral crystal from which the upper facet T and the lower facet C are formed, to provide the table and culet, respectively. These cuts are shown in dotted line, superimposed upon an illustration of a form the natural octahedral crystal. The difference in hardness in the diamond is frequently explained by the fact that the grain runs in different directions. In the illustrated crystal the faces h are parallel to two crystallographic axes which are shaded to indicate the optimum polishing directions by the arrow heads. Faces d, indicated by the direction of the arrow, are also parallel to a crystallographic axis. Faces O are inclined to three crystallographic axes.

In accordance with my invention, I provide in one embodiment, twelve basic or blocking cuts, more particularly shown in Figure 1, for the bezel portion of the diamond, providing the table 20, the sides 21 and the blocking or basic facets 22. These basic or blocking facets 22, while symmetrical about the axis perpendicular to the table 20, are, in the main, non-coincident or angularly disposed to the three main crystallographic axes of the crystal shown in Figure 1A, with reference to which the faces h, d and O have been described.

The pavilion portion 27 in this embodiment is

provided with twelve basic or blocking facets, numbered 28, and with a culet 28a—see Figures 2A and 5, thus outlining the basic or blocking facets shown in Figures 1, 2 and 2A, which includes a relatively thick girdle forming portion 29. From a comparison of Figure 2A and this same figure superimposed in dotted lines in Figure 1A, it will be seen that the twelve basic or blocking facets 22 and 28 for the bezel and pavilion, respectively, are constituted by the portions of four cross-worked blocking facets, with two blocking facets intermediate between two of each of the adjacent cross-worked blocking facets. The right angularly directed planar intersecting axes are shown in Figure 1A to run midway between the remnants of the four cross-worked blocking facets with each of the two intermediate blocking facets therebetween, giving a total of twelve basic facets 22 in the bezel portion and twelve basic facets 28 in the pavilion portion, each subtending an angle of 30°. Thereafter, the brillianteering facets are applied.

For the bezel portion, a series of triangular facets 23 are formed by brillianteering to take down a portion of the rib 24, and the corner 25 to form a new table terminating side 26 extending halfway into each of the sides 21 previously described. Repeating these facets twelve times will form a table of twelve sides, or outline a dodecagon, each side of which table is defined by an edge 26. Thereafter, facets 27a are formed to each side of the rib line 24 below the apex 28b adjacent the bruted girdle forming portion 29, to form a girdle 29a of half normal thickness at this stage and leaving twelve polygonal facets 24a. This provides the bezel portion with forty eight brillianteering facets, exclusive of the table.

The pavilion facets are formed by superimposing two facets 32, terminating adjacent the girdle to complete the girdle 29a approximately half the original thickness of the bruted girdle 29. These facets 32 are formed to each side of every rib forming portion 31, cutting a little further into the girdle, leaving the polygonal diamond shaped facet 30 and resulting in twenty four facets 32, which terminate adjacent the girdle, when repeated about each pavilion rib 31, thus providing a total of thirty six pavilion facets, exclusive of the culet.

The completed diamond, as shown in Figure 5, therefore has formed thereon forty eight bezel facets and thirty six pavilion facets, totalling eighty four facets, exclusive of the table and culet.

It will be observed that in each instance the brillianteering facets are symmetrically formed but angularly directed obliquely to the three main crystallographic axes and angularly to the crown of the diamond, as distinguished from substantially normal to these three main axes.

This method of cutting the material, while increasing the total number of the blocking cuts or basic facets and the brillianteering facets, I have found, permits a faster brillianteering operation in proportion to the number of facets, due to the angular obliqueness of facetting action to the normal grain surface of the diamond. The skilled brillianteerer experiences a new touch, in accordance with my method, speeding up the production, even though the number of facets is disproportionately increased.

Apparent brilliancy is increased and beauty of contour is enhanced over the old brillianteering methods known to me, especially in regard to polygonal shaped facets formed on the bezel and

pavilion. Symmetry of formation of the brilliantering facets assures uniformity of operation as each series of brilliantering facets is imposed upon the blocked or basic facets.

The departure from prior brilliantering for the old brilliant type of diamond will be appreciated by reference to Figures 14, 15 and 16, where the conventional octagon work, after cross work, is illustrated, and preceding the conventional brilliantering which has heretofore resulted in fifty six brilliantering facets—that is, in forming thirty two facets in the bezel forming portion and twenty four facets in the pavilion forming portion.

Under the octagon working system, there is greater likelihood of coincidence in polishing in parallelism with the grain of the natural crystal, requiring considerable shifting of the diamond in order to dispose the diamond with its grain perpendicular to the line of rotation of the skeif. By my method, which relies upon a displacement of the plane of the blocking of basic facets 22 and 28 of the bezel and pavilion, respectively, to a fraction of the angles between the normal crystallographic axes of the diamond, increased blocking and brilliantering speed is achieved, with less likelihood of encountering a parallelism of the grain with the line of rotation of the skeif.

In Figures 6 to 8 another form of the invention has been disclosed in which the diamond is of Swiss cut, but constructed in accordance with this invention. Figures 6 and 7 show basic or blocking cuts taken. In this figure the diamond already has the dodecagon shaped table 32a. This table is formed with twelve sides 33 which have been formed by taking down the rib as 24 after blocking, as in Figure 1 according to the dodecagon blocking. These twelve sides 33 outline substantially triangular facets 34 which extend completely with their apices adjacent the girdle 35 of the diamond. In between the Swiss cut facets 34 there are the blocking or main polished facets 36. Reference numerals 37 (see Figure 6) illustrate the completed faceted bezel of the diamond.

The diamond also is provided with a faceted base or pavilion 38 which consists of twelve radiating polygonal blocking or main facets 39 generally diamond shaped and twenty four smaller outer facets 40 generally triangular adjacent the girdle 35 as provided by taking down a portion of the rib line 31 (see Figure 2A) of the blocked diamond.

In Figure 9 a modified form of diamond is disclosed which is made by a combination of the steps used in making the diamond shown in Figures 5 and 8. The faceted bezel or crown of the diamond shown in Figure 5 is provided with the facets thereof in combination with the method of forming the faceted pavilion 38 of the diamond shown in Figure 8. The various faceted portions of the crown and of the pavilion have been identified by like reference numerals.

In Figure 10 still another modified form of diamond has been disclosed in which another combination is shown. In this diamond, the faceted crown 37 of the diamond shown in Figure 8 has been used in combination with the faceted pavilion 27 disclosed in Figure 2A. Like faceted surfaces have been identified by like reference numerals.

In Figures 11 to 13, still another design of diamond is shown which we may call a sextodecagon for a sixteen blocking cut diamond. This diamond has a table 45 formed with sixteen straight sides 46. The diamond has a faceted

10 bezel or crown 47 which is formed from sixteen triangular inner facets 48 adjacent the table 45, sixteen diamond shaped blocking or main facets 49, and thirty two triangular outer facets 50. Adjacent the girdle 51 a faceted pavilion 52 is provided and is formed with sixteen diamond shaped radiating blocking or main facets 53 and thirty two smaller outer triangular faceted portions 54 adjacent the girdle 51.

15 As distinguished from the embodiment described in connection with the dodecagon blocking system, the sextodecagon blocking system derives the sixteen blocking cuts from the remnants of the four cross-worked blocking facets with three blocking facets intermediate two of each of the adjacent cross-worked blocking facets.

20 In Figures 14 to 16, the standard octagon blocking diamond procedure as heretofore practiced is shown, so that the new design may be easily understood and recognized. This old procedure is shown as based upon the usual table 55 with eight straight sides 56 defining eight main flat polished facets 57, forming the octagon work for the blocking facets. It is provided with the usual girdle 25 58 and the blocked pavilion 59 having eight basic or blocking facets 60.

25 In general under my procedure in accordance with the embodiments illustrated, the basic or blocking facets subtend an angle less than 22.5° and no more than 30° as compared with a subtended angle of 45° by conventional procedure. While by my invention symmetry of the basic or blocking facets is secured, the shifting of the diamond to present the most effective cross grain 30 of the diamond perpendicular to the line of rotation of the skeif is minimized.

35 Thus, also, by my invention, the main facets in the bezel or crown, such as the facets 22 in the embodiment illustrated in Figures 1 to 5, lying between the table and the girdle, and the main pavilion facets lying between the culet and girdle, have their widest dimensions subtend an angle no greater than 30°. Thus, also, in the embodiment illustrated in Figures 12 and 13, the central or main facets 49 of the bezel 47 lying between the table 45 and the girdle 51, and the main facets 53 lying between the culet and the girdle likewise subtend an angle, at their greatest 40 dimension, no greater than 22.5°.

45 In the embodiment illustrated in Figures 6 and 7, the main facets 36 and 39, respectively, on the bezel and pavilion, at their widest portion subtend an angle no greater than 30°.

50 Accordingly, in accordance with my invention, the principal facets, as well as the facets adjacent the girdle and table, each subtend an angle no more than 30° and, in instances, no more than 22.5°, providing a relationship of the surfaces faceted to the grain of the gem which simplifies the rate of brilliantering.

55 The basic or blocking facets likewise are formed to subtend an angle less than 30° and, in instances, 22.5°, to carry out the same relationship of grain lines to the line of rotation of the skeif, greatly simplifying the blocking as well as the brilliantering operation.

60 The symmetry of the formation of the blocking facets or the brilliantering operation provides uniformity of touch to the brillianteer, increasing the speed of production. Coordinately, also, in accordance with some of the embodiments illustrated, the polygonal facets appearing on the crown or bezel and on the pavilion are elongate 65 and at no time subtend an angle greater than 40°.

but below the same and preferably below 30° , as in the case of the embodiments illustrated in Figures 1 to 5, 7, 8 and 11 to 13, or for the Swiss cut facets where the facets are preferably formed to subtend an angle of 30° , though 22.5° is contemplated for a diamond based upon sixteen blocking or basic cuts. Symmetry of facets, to form an even number, is preferred and, accordingly, the subtended angle may be less than 22.5° within these prescriptions as to symmetry of location.

For convenient of reference, the brilliant-cut type diamond in accordance with one embodiment of my invention, as described and disclosed, will be referred to as to dodecagon blocking system, which is applicable to the bezel portion, the pavilion portion or to both of these portions. In another embodiment of my invention, as described and disclosed, the brilliant-cut type diamond will be referred to as the sextodecagon blocking system, which is likewise applicable to the bezel portion, the pavilion portion or to both of these portions.

It is to be understood, however, that I contemplate within the spirit of my invention to combine in one diamond, on either the bezel portion or the pavilion portion, faceted portions on the basis of the dodecagon blocking system or the sextodecagon blocking system alternatively, combined with the octagon blocking system on the remaining portion. Thus, the bezel portion may be made in accordance with my invention under the dodecagon blocking system or the sextodecagon blocking system and the pavilion portion of such a type diamond may be made under the octagon blocking system. Conversely, the bezel portion may be made under the octagon blocking system and the pavilion portion made under the dodecagon or sextodecagon blocking system. The combination may be found expedient due to a condition of the bruted stock and the grain condition of the diamond in the bruted stock employed.

By the "dodecagon blocking system" and the "sextodecagon blocking system," I mean to include the formation of the basic blocking cuts of four cross-worked blocking cuts with two and three intermediate blocking cuts respectively between two of each of adjacent cross-worked blocking cuts, providing, respectively, twelve and sixteen blocking cuts which are each of substantially the same magnitude.

It is understood, however, that while I have provided an explanation or theory of operation for my invention, predicated upon experience in practicing the same, which may serve as a guide to secure optimum results, I do not intend to be limited thereby, and further scientific study or those skilled in the art may provide other explanations for the beneficial results secured by my invention.

In the specification and claims where I refer to "brillanteering," I mean to include thereby the polishing operation for diamonds for the formation of a triangular facet by polishing the intersecting corners of two blocking facets and the table or girdle, as distinguished from a blocking facet which extends the full length between the girdle to either the table or culet.

Having thus described my invention and illustrated its use, what I claim as new and desire to secure by Letters Patent is:

1. In the method of forming diamonds into brilliants from the bruted stock, the steps which include forming on at least one of the bezel and

crown portions thereof blocking cuts directed by cross-working to provide four cross-worked blocking facets with at least two intermediate blocking facets between two of each of the adjacent cross-worked blocking facets each of which subtend an angle less than 40° , extending between at least the table and culet axially and the girdle peripherally, and imposing brillanteering facets on the blocking cuts thus formed.

6 10 2. In the method of forming diamonds into brilliants from the bruted stock, the steps which include forming the table and culet, providing symmetrically directed blocking facets by cross-working with at least two intermediate blocking facets between two of each of the adjacent cross-worked blocking facets and extending in the crown and pavilion axially from the table and culet, respectively, to the girdle portion, and circumferentially extended symmetrically to subtend an angle in each blocking facet less than 40° .

15 20 3. In the method of forming diamonds into brilliants from the bruted stock, the steps which include forming the table and culet and blocking facets on the crown and pavilion portions, respectively, by cross-working with no less than two and no more than three intermediate blocking facets between two of each of the adjacent cross-worked blocking facets and extending axially from the table and culet, respectively, to the girdle portion peripherally, each blocking facet being substantially equal and subtending an angle of the magnitude no greater than 30° and no smaller than 22.5° to provide no less than twelve and no more than sixteen blocking facets on the crown and pavilion, respectively, leaving a girdle portion.

25 30 4. In the method of forming diamonds into brilliants from the bruted stock, the steps which include forming the table and culet and blocking facets on the crown and pavilion portions, respectively, by cross-working with no less than two and no more than three intermediate blocking facets between two of each of the adjacent cross-worked blocking facets and extending axially from the table and culet, respectively, to the girdle portion peripherally, each blocking facet being substantially equal and subtending an angle of the magnitude no greater than 30° and no smaller than 22.5° to provide no less than twelve and no more than sixteen blocking facets on the crown and pavilion, respectively, leaving a girdle portion; and then brillanteering the ridges cut into the table, culet and girdle to provide brillanteered facets of polygonal contour, and substantially triangular facets intermediately spaced between the polygonal facets adjacent the girdle, including the formation of substantially triangular facets adjacent the table.

35 40 5. In the method of forming diamonds into brilliants from the bruted stock, the steps which include providing the bruted stock with symmetrically arranged blocking facets of equal magnitude on the crown and pavilion, respectively, of an even number in excess of eight by cross-working, with at least two intermediate blocking facets between two of each of the adjacent cross-worked blocking facets, and brillanteering the ridges so formed to provide brillanteered intermediate facets, the intermediate facets extending between the table and the girdle in the bezel portion and from the culet to the girdle in the pavilion portion, the facets extending between the table and the girdle on the bezel portion being 45 50 55 60 65 70 75 polygonal, with the brillanteered intermediate

facets adjacent the table and girdle being substantially triangular.

6. In the method of forming diamonds into brilliants from the bruted stock in accordance with claim 5 wherein the blocking facets are twelve in number on each of the bezel and pavilion portions and with twelve substantially triangular intermediate brillianteed facets adjacent the table and twenty four intermediate, substantially triangular facets adjacent the girdle on the bezel portion, there being formed twenty four substantially triangular intermediate facets on the pavilion portion adjacent the girdle.

7. In the method of forming diamonds into brilliants from the bruted stock in accordance with claim 5 wherein the blocking facets are sixteen in number on each of the bezel and pavilion portions and with sixteen substantially triangular intermediate brillianteed facets adjacent the table and thirty two intermediate, substantially triangular facets adjacent the girdle on the bezel portion, there being formed thirty two substantially triangular intermediate facets on the pavilion portion adjacent the girdle.

8. A brilliant-cut type diamond having a table and culet including a faceted bezel and pavilion to each side of the girdle portion, symmetrically disposed main facets on said bezel and pavilion extending to the table and culet, outlining symmetrically on said table the corners of at least a twelve straight sided polygon after brillianteed and including between each main facet, brillianteed facets terminating adjacent the girdle.

9. A brilliant-cut type diamond having a table portion, a culet portion and a girdle portion defining the bezel and pavilion of the diamond, having symmetrically disposed main bezel and pavilion facets extended to each side of the girdle axially toward the table and culet, respectively, of the order of an even number of twelve or greater, with intermediate brillianteed facets adjacent the girdle in the bezel and pavilion portion, the main facets outlining the corners of a polygon of at least twelve sides on the table.

10. A brilliant-cut type diamond including a table, a culet disposed to either side of a girdle defining a bezel portion and pavilion portion, at least twelve symmetrically disposed main facets extending in the bezel and pavilion portion from the table and culet, respectively, to the girdle, intermediate brillianteed facets adjacent the table and intermediate brillianteed facets between each of the main facets adjacent the girdle in the bezel and pavilion portions.

11. A brilliant-cut type diamond including a faceted bezel portion and a pavilion portion to each side of the girdle portion, and a table on said bezel portion, at least one of said bezel and pavilion portions having symmetrically disposed thereon and extending on said bezel and pavilion portions, symmetrically disposed main facets based upon the dodecagon blocking system and including to each side of the main facets based upon the dodecagon blocking system, brillianteed facets terminating adjacent the girdle.

12. A brilliant-cut type diamond including a faceted bezel portion and a pavilion portion to each side of the girdle portion and a table on said bezel portion, at least one of said bezel and pavilion portions having symmetrically disposed thereon and extending on said bezel and pavilion portions, symmetrically disposed main facets based upon the dodecagon blocking system and including to each side of the main facets based upon the dodecagon blocking system, brillianteed facets terminating adjacent the girdle.

13. A brilliant-cut type diamond including a table, a culet disposed to either side of a girdle defining a bezel portion and a pavilion portion, at least one of said portions having basic facets founded upon the dodecagon blocking system.

14. A brilliant-cut type diamond including a table, a culet disposed to either side of a girdle defining a bezel portion and a pavilion portion, at least one of said portions having basic facets founded upon the dodecagon blocking system.

facets adjacent the table and girdle being substantially triangular.

6. In the method of forming diamonds into brilliants from the bruted stock in accordance with claim 5 wherein the blocking facets are twelve in number on each of the bezel and pavilion portions and with twelve substantially triangular intermediate brillianteed facets adjacent the table and twenty four intermediate, substantially triangular facets adjacent the girdle on the bezel portion, there being formed twenty four substantially triangular intermediate facets on the pavilion portion adjacent the girdle.

7. In the method of forming diamonds into brilliants from the bruted stock in accordance with claim 5 wherein the blocking facets are sixteen in number on each of the bezel and pavilion portions and with sixteen substantially triangular intermediate brillianteed facets adjacent the table and thirty two intermediate, substantially triangular facets adjacent the girdle on the bezel portion, there being formed thirty two substantially triangular intermediate facets on the pavilion portion adjacent the girdle.

8. A brilliant-cut type diamond having a table and culet including a faceted bezel and pavilion to each side of the girdle portion, symmetrically disposed main facets on said bezel and pavilion extending to the table and culet, outlining symmetrically on said table the corners of at least a twelve straight sided polygon after brillianteering and including between each main facet, brillianteed facets terminating adjacent the girdle.

9. A brilliant-cut type diamond having a table portion, a culet portion and a girdle portion defining the bezel and pavilion of the diamond, having symmetrically disposed main bezel and pavilion facets extended to each side of the girdle axially toward the table and culet, respectively, of the order of an even number of twelve or greater, with intermediate brillianteed facets adjacent the girdle in the bezel and pavilion portion, the main facets outlining the corners of a polygon of at least twelve sides on the table.

10. A brilliant-cut type diamond including a table, a culet disposed to either side of a girdle defining a bezel portion and pavilion portion, at least twelve symmetrically disposed main facets extending in the bezel and pavilion portion from the table and culet, respectively, to the girdle, intermediate brillianteed facets adjacent the table and intermediate brillianteed facets between each of the main facets adjacent the girdle in the bezel and pavilion portions.

11. A brilliant-cut type diamond including a faceted bezel portion and a pavilion portion to each side of the girdle portion, and a table on said bezel portion, at least one of said bezel and pavilion portions having symmetrically disposed thereon and extending on said bezel and pavilion portions, symmetrically disposed main facets based upon the dodecagon blocking system and including to each side of the main facets based upon the dodecagon blocking system, brillianteed facets terminating adjacent the girdle.

12. A brilliant-cut type diamond including a faceted bezel portion and a pavilion portion to each side of the girdle portion and a table on said bezel portion, at least one of said bezel and pavilion portions having symmetrically disposed thereon and extending on said bezel and pavilion portions, symmetrically disposed main facets based upon the dodecagon blocking system and including to each side of the main facets based upon the dodecagon blocking system, brillianteed facets terminating adjacent the girdle.

13. A brilliant-cut type diamond including a table, a culet disposed to either side of a girdle defining a bezel portion and a pavilion portion, at least one of said portions having basic facets founded upon the dodecagon blocking system.

14. A brilliant-cut type diamond including a table, a culet disposed to either side of a girdle defining a bezel portion and a pavilion portion, at least one of said portions having basic facets founded upon the dodecagon blocking system.
